UNITED STATES PATENT OFFICE.

CHARLES E. GOODWIN, OF LAWRENCE, MASSACHUSETTS.

BRAKE-CLAMP.

SPECIFICATION forming part of Letters Patent No. 665,208, dated January 1, 1901.

Application filed July 12, 1900. Serial No. 23,839. (No model.)

To all whom it may concern:

Be it known that I, CHARLES E. GOODWIN, a citizen of the United States, residing at Lawrence, in the county of Essex and State of Massachusetts, have invented new and useful Improvements in Brake-Clamps, of which the following is a specification.

In the accompanying drawings, Figure 1 is a side view of the clamp. Fig. 2 is a transverse section at $x x$. Fig. 3 is a transverse section at $y y$. Fig. 4 is a detail view, and Fig. 5 shows the mode of application of the clamp.

The invention relates to clamps for taking up the slack of the brake-bearing in order to facilitate connecting the bottom rod of passenger-trucks and for other like purposes, as hereinafter set forth.

In the accompanying drawings the letter A designates the main bar, which is made straight, with parallel sides, and is provided at one end with a transverse head or short bar B. The end of this short bar is provided with a threaded bearing for engagement with the threaded portions of the screw C, the inner end of which is seated in a recess or bearing d in the back of the hook-slide E, which is formed with a loop F, engaging the main bar. This hook-slide is designed to engage a brake-beam of any style. The end of the screw C is secured in its bearing in the back of the hook by means of a set-screw, as indicated at g. At the other end of the main bar is the axle-grip H, having the main or outer clamp-hook k and the inner hook projection l, these hook projections extending from the body portion m, which is provided with a longitudinal slideway or bearing n, through which the end of the main bar A is extended. The slideway or bearing n is enlarged somewhat toward its inner end in tapering form to allow play on the main bar and to receive the steel spring s, which is designed to hold the inner projection p of the clamp in engagement with a notch t of the main bar, said bar having a series of said notches, forming a rack, as indicated in the drawings.

Z indicates a handle-bar at the outer end of the screw C.

The brake-bars employed on railway-car trucks are of different styles and the wheels of various sizes within certain limitations, and it is designed by the inventor to provide a clamp which is easily adjusted and applied without liability of slipping when the strain is applied.

When the clamp is applied, the axle-grip is adjusted to approximate position on the main bar, when it is held automatically by the action of the spring after it is applied to the wheel-axle, the brake-hook is placed in position on the brake-beam, and by means of a few turns of the screw the brake-shoes are pressed up against the wheels, so that the length of the brake-rod can be readily taken and applied.

The detachment of the instrument from the axle and from the brake-beam is easily and quickly effected.

The clamp is strong and durable and proves very efficient for the purposes in view.

Having described this invention, what I claim, and desire to secure by Letters Patent, is—

1. The clamp consisting of the notched main bar, the adjustable axle-grip at one end of said bar and adapted to engage the notches of said bar, the adjustable slide upon the opposite end of said bar adapted for engagement with the brake shoe or beam, the cross-head of said bar, and the screw having a threaded engagement with said cross-head and bearing at its end portion upon said slide, substantially as specified.

2. The combination with the notched main bar and its cross-bar having a threaded eye, of a spring-held adjustable hook on the notched end of the bar, and on the other end the adjustable hook the adjusting-screw, and the recess or bearing of said hook engaging the end of said screw, substantially as specified.

In testimony whereof I affix my signature in presence of two witnesses.

CHARLES E. GOODWIN.

Witnesses:

MERRILL N. HOWE,
P. BEATRICE BUXTON.
